SENSITIVE PHOTOGRAPHIC ELEMENT

Albert A. Young and Alfred D. Slack, Rochester, N. Y., assignors, by mesne assignments, to Eastman Kodak Company, Jersey City, N. J., a corporation of New Jersey

Application January 30, 1935, Serial No. 4,129

3 Claims. (Cl. 95—8)

This invention relates to a photographic film having upon its emulsion or sensitized surface a protective layer which protects it, while sensitive, from abrasion and from the effects of moisture, and which is permeable to and incompletely removed in an alkaline developing bath, a sufficient quantity of the coating remaining after ordinary photographic processing to give a high degree of resistance to scratching to the finished film. This is useful in all photographic film, particularly in motion picture film and is especially desirable in film bearing sound records.

Efforts have been made to lubricate the picture surface of motion picture film after exposure and development, but this leaves the emulsion layer exposed to abrasion while it is being run through the camera and while it is being processed. It has also been proposed to coat sensitive films, for the purpose of waterproofing them, with substances which will be removed during development. Plainly, such coatings can give no protection of any kind after the development of the film, since they are no longer present.

Our invention is an improvement over both these processes inasmuch as it provides a means for protecting films from abrasion both before and after development.

We have found that natural waxes, such as Montan wax, carnauba wax, ceresin wax, paraffin, beeswax, candelilla wax, and the like, meet our requirements, although we also include in the term "wax" synthetic compounds having the physical properties of wax, such as the chlorinated naphthalenes and other "synthetic" waxes, a number of which are on the market which are only incompletely removed in ordinary developing baths.

Reference is made to the accompanying drawing, the single figure of which shows a section on an exaggerated scale of a film embodying our invention. In this figure, 1 indicates a support of a suitable composition, customarily a cellulose ester composition, but which may be of any type useful as a photographic support; 2 indicates the sensitive layer, ordinarily a gelatino silver halide emulsion and 3 is the protective layer.

The wax is ordinarily applied from solution in a solvent which does not attack layers 1 or 2. It is applied by ordinary coating methods either before or after the emulsion layer is thoroughly dry, preferably the latter. The dilution may vary within wide limits depending on the method of

coating used and the desired thickness of the coating. The following is a suitable formula:

	Grams
Chloroform	100
Carnauba wax	.05

Ethylene dichloride may be substituted for chloroform as a solvent, and any of the natural or synthetic waxes not entirely removed in the developing baths may be used to replace carnauba.

After the solvent has evaporated, there is left a coating 3 which protects the layer 2 while sensitive. Even though the wax is largely removed in the developer, there is enough left to have a markedly beneficial effect in the protection of the finished film, thereby rendering a later waxing unnecessary.

We consider as included within our invention all modifications and equivalents falling within the scope of the appended claims.

Having thus described our invention, what we claim as new and desire to be secured by Letters Patent of the United States is:

1. A photographic element comprising a support, a light-sensitive silver halide photographic emulsion layer thereon, and a thin, adherent, abrasion-resistant coating over the sensitive emulsion layer and forming the surface of the photographic element, the abrasion-resistant layer comprising a wax which is permeable to and incompletely removable in an alkaline developing bath.

2. A photographic element comprising a support, a light-sensitive silver halide photographic emulsion layer thereon, and a thin, adherent, abrasion-resistant coating over the sensitive emulsion layer and forming the surface of the photographic element, the abrasion-resistant layer comprising a natural wax which is permeable to and incompletely removable in an alkaline developing bath.

3. A photographic element comprising a support, a light-sensitive silver halide photographic emulsion layer thereon, and a thin, adherent, abrasion-resistant coating over the sensitive emulsion layer and forming the surface of the photographic element, the abrasion-resistant layer comprising carnauba wax, which is permeable to and incompletely removable in an alkaline developing bath.

ALBERT A. YOUNG.
ALFRED D. SLACK.
